(57) **CLAIM**

The ornamental design for a barrel nut assembly, as shown and described.

DESCRIPTION

FIG. 1 is a top front right side perspective view of a barrel nut assembly showing the design of the present disclosure in its combined configuration;

FIG. 2 is a bottom rear left side perspective view of the barrel nut assembly of FIG. 1;

FIG. 3 is a front elevation view of the barrel nut assembly of FIG. 1;

FIG. 4 is a rear elevation view of the barrel nut assembly of FIG. 1;

FIG. 5 is a left elevation view of the barrel nut assembly of FIG. 1;

FIG. 6 is a right elevation view of the barrel nut assembly of FIG. 1;

FIG. 7 is a top plan view of the barrel nut assembly of FIG. 1;

FIG. 8 is a bottom plan view of the barrel nut assembly of FIG. 1;

FIG. 9 is a top front right side perspective view of the barrel nut assembly showing the design of the present disclosure in its exploded configuration;

FIG. 10 is a bottom rear left side perspective view of the barrel nut assembly of FIG. 9;

FIG. 11 is a front elevation view of the barrel nut assembly of FIG. 9;

FIG. 12 is a rear elevation view of the barrel nut assembly of FIG. 9;

FIG. 13 is a left elevation view of the barrel nut assembly of FIG. 9;

FIG. 14 is a right elevation view of the barrel nut assembly of FIG. 9;

FIG. 15 is a top plan view of the barrel nut assembly of FIG. 9; and,

(Continued)

FIG. 16 is a bottom plan view of the barrel nut assembly of FIG. 9.

The evenly spaced dashed lines depict portions of the barrel nut assembly that form no part of the claimed design.

1 Claim, 12 Drawing Sheets
